UNITED STATES PATENT OFFICE.

GEORGE MARSH AND VINDEX ARNOLD, OF MARSHALL, MICHIGAN.

AUTOMATIC GRAIN-METER.

SPECIFICATION forming part of Letters Patent No. 297,614, dated April 29, 1884.

Application filed February 15, 1884. (No model.)

To all whom it may concern:

Be it known that we, GEORGE MARSH and VINDEX ARNOLD, citizens of the United States, residing at Marshall, in the county of Calhoun 5 and State of Michigan, have invented certain new and useful Improvements in Automatic Grain-Scales, of which the following is a full, clear, and exact description.

The object of this invention is to improve 10 and simplify the construction of automatic machines for weighing or measuring grain; and the invention relates particularly to that class of such machines in which a two-compartment receptacle is suspended in such manner that when one compartment is filled with grain the receptacle descends, the grain is diverted to the other compartment, and simultaneously the outlet of said filling compartment is closed, and the outlet of the filled compartment opened, and so on while the supply 20 of grain lasts.

The improvements consist, mainly, in the means for diverting the grain from one compartment to the other, and opening and closing the outlets, substantially as hereinafter 25 particularly set forth and claimed.

In the accompanying drawings, in the several figures of which like parts are similarly designated, Figure 1 is a perspective view of 30 our improved machine. Fig. 2 is a vertical section on the plane of line xx , Fig. 1; and Fig. 3 is a rear elevation of the machine, showing the registering mechanism uncovered.

A suitable frame-work, A, is provided, consisting, for example, of upright posts a , cross-pieces b , and stringers c , properly connected.

B is the grain-receptacle, made as usual, with a central vertical partition dividing it into two compartments of preferably equal capacity, 40 each having a larger outlet than inlet. Each of these outlets is provided with a gate or hinged valve, d , hinged to open from each other.

e is the funnel or hopper. This receptacle 45 is suspended within the frame by means of a forked lever, C, the forked ends ff of which have anti-friction journals gg , engaging bearings hh , attached to the receptacle. This forked lever is fulcrumed on the frame in boxes 50 ii by the lateral pivots jj of its forked portion. The arm k of the lever extends from the

receptacle, and is provided with a weight or counterpoise, l , adjustable thereon to provide for discharging from the receptacle different quantities of grain. The lever is thus of the 55 third kind. The anti-friction bearings and fulcra for said lever are preferably of the well-known knife-edge class.

Within the receptacle in line with the partition is a shaft, m , borne by the side walls 60 of said receptacle, and provided with the usual gate or valve, n , to be alternately thrown across and cover the mouths of the compartments beneath the hopper or funnel, to direct the incoming grain from the hopper into one or the 65 other of the compartments. The gate is supported over either mouth by stops o on the receptacle.

Outside the receptacle on the shaft m , at one end, is a V-shaped rock-lever, p , said lever being fixed to the shaft at the apex of the V, and serving as the medium through which the shaft and its attached gate are moved. The arms of this lever are of such divergence with respect to the axis of the shaft that as they are 75 moved their upper ends fall slightly over and beyond the said axis, or what is called in workshop terms, the "dead-center" of the rock-lever, for a purpose presently appearing. The ends of the arms of this rock-lever and the opening ends of the two discharge gates or valves dd are connected by rods q , the joints being free or hinge-like. The rock-lever is notched at rr on opposite sides of the shaft and in the lower surface, and these notches are engaged 85 by a fixed finger, s , projecting upward from one of the cross-pieces b of the frame. As the receptacle fills, the weight of grain required overbalances the weight l , and said receptacle descends, moving the lever C on 90 its fulcra. In so descending, the notch r in that side of the rock-lever next the empty compartment (the gate n , covering said empty compartment) comes in contact with the finger s , and said lever is by said finger consequently 95 thrown over to the other side, carrying the gate n over to and closing the mouth of the filled compartment. This movement of the rock-lever draws up the rod, connecting it with the discharge-valve of the empty compartment and closes the discharge end of such compartment; and inasmuch as the arm of the 100

lever carrying the rod of that gate passes the axial line or so-called "dead-center" of the rock-lever, it follows that the discharge-valve of the empty compartment (now filling) will be 5 locked or positively held in the closed position without other fastenings. Simultaneously with this closing of the empty compartment, the rod connecting the rock-lever with the discharge-valve of the other compartment will 10 descend and positively open the discharge-valve of that compartment; and inasmuch as the outlet is larger than the inlet of these compartments, they will empty much more rapidly than they fill, and consequently allow the 15 receptacle to rise under the weight of the counterpoise, to again fall as the counterpoise is overbalanced by the filling compartment.

Instead of notching the rock-lever for the engagement of the finger, we may employ an 20 independent angle-plate fast to the shaft.

As the turning of the shaft *m* marks the filling of a compartment, any registering mechanism—say the train of wheels *E*—may be connected therewith, to obtain the aggregate of 25 compartments full discharged.

The first or unit wheel may be operated upon both turns of the shaft by the pawls *t*, arranged at diametric points of the shaft *m*; but we do not limit our invention to such 30 registering mechanism.

What we claim, is—

1. The combination, in a grain-meter, of a counterpoised receptacle divided into compartments, a gate arranged to alternately cover 35 the inlet of one or the other of such compartments, a rock-lever connected with such gate, and a stationary spring-finger to engage such rock-lever to throw it first to one side and

then the other, to move the gate from the empty to the full compartments, substantially as 40 shown and described.

2. The combination, in a grain-meter, of the counterpoised receptacle divided into two compartments, a gate arranged to cover the inlets to said compartments alternately, a rock-lever 45 connected with the gate, discharge-valves to said compartments, rods connecting said rock-lever and valves, and a stationary finger engaging said rock-lever, to throw its arms and the attached rods beyond the axis or dead-center of the lever as the receptacle descends, 50 to positively lock the closed discharge-valve, substantially as described.

3. The combination, in a grain-meter, of a frame, a forked lever fulcrumed thereon, a 55 counterpoise on said lever, a receptacle hung in said forked lever and divided into two compartments, a gate arranged to cover the inlets to said compartments alternately, a rock-lever connected with the gate, discharge-valves to 60 said compartments, rods connecting said rock-lever and valves, and a stationary finger engaging said rock-lever, to throw its arms and the attached rods beyond the axis or dead-center of the lever, as the receptacle descends, 65 to positively lock the closed discharge-valve, substantially as described.

In testimony whereof we have hereunto set our hands this 13th day of February, A. D. 1884.

GEORGE MARSH.
VINDEX ARNOLD.
